METHOD OF AND MACHINE FOR TREATING
AND LAYING STRIP MATERIAL FROM
PACKAGES

Albert C. Fischer, Chicago, Ill.

Application January 26, 1940, Serial No. 315,681

12 Claims. (Cl. 94—39)

This invention relates to machines for treating and depositing material while being advanced over a space for receiving the same. More particularly, the invention concerns machines for treating and filling the crevices at sectional joints in concrete paving or the like, and for laying roofing paper or other similar materials upon flat surfaces.

The invention further contemplates and has for its objects an improved strip convertible into a plastic or semi-fluid condition upon the application of heat by said machines to provide a medium for sealing and securing the deposited materials in place; a new package embodying such strip; a new process of preparing the space for receiving the strip and of depositing the strip and other materials within said space; and novel apparatus for carrying out said process. An additional object is the provision of a process of and machine for laying a compressible strip within a paving joint crevice or the like.

Fig. 1 is a side elevational view of a machine constructed in accordance with the principles of the present invention and which is adapted to clean a paving crevice or the like, to apply a cementitious material to the crevice and to lay a filler strip within such crevice, there being parts broken away for clarity;

Fig. 2 is a horizontal sectional view taken through said machine substantially upon the line 2—2 of Fig. 1;

Fig. 3 is a fragmentary sectional view illustrating a modified form of feeding passage adaptable to the machine of Figs. 1 and 2;

Fig. 4 is a fragmentary sectional view taken transversely of adjacent paving slabs, illustrating a crevice between such slabs and a paving filler strip therein of the type adapted to be inserted by the apparatus shown in Fig. 3;

Fig. 5 is a modified form of machine for cleaning and lining a paving joint crevice with a cementitious material preparatory to its receiving a filler strip;

Fig. 6 is a filler strip laying machine which is adapted to deposit a filler strip in a paving joint crevice;

Fig. 7 is a modified form of machine which is adapted both to clean a paving crevice and to lay a filler strip therein, the view being a side elevation with parts broken away for clarity;

Fig. 8 is a horizontal sectional view taken on the line 8—8 of Fig. 7;

Fig. 9 is a vertical sectional view taken through a modified form of machine which is adapted to lay roofing paper or the like upon a flat surface, to melt a strip of adhesive sealing material and to apply the melted material to the surface in advance of laying the paper thereon; and

Fig. 10 is a transverse vertical sectional view taken on the line 10—10 of Fig. 9.

Referring now to the drawings and particularly to Figs. 1 and 2 thereof, the machine there shown is for treating a crevice 10 which is between two adjacent paving slabs or the like 11 and 12. The lower part of the crevice 10, when the crevice is between paving slabs, will normally be filled by an asphaltic plank 13. Both the slabs 11 and 12 and the lower edge of the plank 13 rest upon a prepared earth bed 14.

The machine frame comprises a pair of parallel side members 15 and 16. The side member 15 has a rearwardly and upwardly inclined section 17 offset outwardly from the front or main body of this member. Similarly, an upwardly inclined rear section 18 is offset outwardly from the forepart of the side member 16.

Axle bolts 20, 21, 22 and 23 interconnect the foreparts of the frame members 15 and 16 and have respectively journalled thereon, between said frame members, a cleaner brush 24, a coating applicator brush 25, a combination driving and guide roller 26 and a guide roller 27.

Said brush member 24 has a center section 28 of bristles sufficiently long to reach downwardly into the crevice 10, and sections 29 upon each side thereof with bristles of a length to sweepingly engage the slabs 11 and 12 adjacent to said crevice. Sections 30 and 31 of the brush 25 respectively correspond to the sections 28 and 29 of the brush 24.

The guide and driving roller 26 provides part of the machine running gear, said roller being adapted to bear upon the adjacent edges of the slabs 11 and 12 and having a center flange 32 which is of limited width to enable it to project downwardly into the crevice 10. The guide roller 27 is also provided with a central flange, 33, which is adapted to project downwardly into the crevice.

A part of the machine running gear is comprised of a broad roller or drum 34 of comparatively large diameter. This roller is journalled at its hollow trunnions 35 within countersunk bearing portions 36 of burner shields 37 which are anchored in the offset frame sections 17 and 18. Because of the axial extent of the drum 34 the vehicular machine has adequate lateral support to enable it to stand upright without the assistance of an attendant.

A sleeve (not shown), rotatively disposed upon the bolt 22, is connected with the hub of the driving roller 26 and projects through the frame member 16 where it has a gear 38 connected non-rotatively therewith. Thus the gear 38 is connected for rotation with the driving roller 26. A gear 39 meshes with the gear 38 and is journalled upon a shaft 40 which is anchored in the side member 16 and a bracket member 41 that is

connected to the frame member by bolts 41'. Also rotatively disposed upon the bolt 40 is a sprocket 42, and this sprocket is suitably connected with the gear 39 to be driven thereby.

The bolt 21 rotatively carries a sleeve (not shown) which extends through the frame member 16 where it has fixed thereto sprocket wheels 43 and 44. Said sleeve is fixed to the hub of the brush member 25 whereby said brush member and the sprockets 43 and 44 are connected for rotation in unison. Another sleeve (not shown), rotatively disposed upon the bolt 20, is secured to the hub of the cleaner brush 24 and carries for rotation therewith a sprocket wheel 45. A chain 46 operably connects the sprocket wheels 42 and 43, whereas a chain 47 similarly connects the sprocket wheels 44 and 45. It will be seen, therefore, that when the machine is advanced, toward the left, the frictional engagement of the roller 26 with the slabs 11 and 12 will cause it and the gear 38 to rotate counter-clockwise as indicated by the arrow adjacent to the roller 26 in Fig. 1. The gear 38 then causes the gear 39 and the sprocket wheel 42 to rotate clockwise, and the chain 46 interconnecting the sprocket wheels 42 and 43 is then operable to impart clockwise rotation to the sprocket wheel 43 which, in turn, imparts clockwise rotation to the sprocket wheel 44 and to the applicator brush 25. Chain 47 is then effective for transmitting driving force from the sprocket 44 to the sprocket 45 for imparting clockwise rotation to the brush member 24. In other words, the brush members 24 and 25 are driven through the power transmission mechanism comprising the aforesaid gears, sprockets, and chains, from the driver roller 26 and caused to rotate in the direction opposite to that of said driver roller.

Manipulation and advancement of the machine is accomplished by manual force applied to a backwardly and upwardly extending control shaft 48 having a handle bar 49 attached to its upper end. Said control bar is suitably anchored at its lower end in a socket member 50 which includes a ring 51 carried about a long bolt 52. This bolt 52 is inserted through holes in the back end sections of the frame members 15 and 16 and through spacer sleeves 53 and 54 which are disposed upon opposite sides of the ring 51. When a wing nut 55 is loosened, sufficient play is possible between a serrated edge 56 of the base member ring 51 and a complementary serrated end 57 of the spacer sleeve 54 to permit angular adjustment of the control shaft 48 about the bolt 52. After the desired adjustment is obtained, it is preserved by simply tightening the wing nut 55 for holding the serrations 56 and 57 tightly meshed.

A pair of identical standards each comprising upwardly converging legs 58 and 59 rise respectively from the frame side members 15 and 16 and are apertured as at 60 at their upper ends for receiving a reel-holding rod 61. This rod 61 is adapted to rotatively carry a reel 62 having a strip 63 of joint filler material wound thereabout. The reel is placed upon the machine by aligning its opposite ends with the standard apertures 60, whereupon the rod 61 is inserted through said apertures and through a center axial opening in the reel. Such reel is removed when desired, by simply withdrawing the rod 61.

This filler strip 63 may be made from a viscous hydrocarbon material such as asphalt having compounded therewith a suitable fibrous material to toughen it and a petroleum oil to increase

its flexibility so that it will unwind readily from the reel in cold weather. Mineral matter such as powdered lime may also be added in amounts up to 30% to harden the strip and to prevent the contiguous surfaces from sticking together upon the reel. While asphalt is named as a suitable material from which to make the strip 63, it is to be understood that any material will do which melts quickly when heated and which has the proper physical characteristics when deposited in the crevice. The free end of the strip is threaded downwardly from the reel through a heater passage generally designated 64. This passage comprises downwardly converging side walls 65 and 66, a front wall 67 which slants backwardly and the lower forward cylindrical periphery of said drum. The lower end of this passage is arranged for registry with the crevice 10 and serves as guiding means for directing the strip 63 into said crevice while the machine is advanced as presently explained.

Heating means comprising burners generally designated 68 are incorporated into the passage structure. Each of these burners 68 includes a gas mixing tube 69 having a plurality of apertures 70 for the admittance of air for forming a combustible mixture with gas vapor discharged from jet members 71 which are in threaded engagement with the extended ends of said tubes 69. Gas vapor under pressure is admitted to the jet members 71 through conduits as 72 and 73. The amount of vapor discharged from the jets and hence the flame intensity is regulatable by conventional valves under control of handles 74.

Jet members 71', in threaded relation with the mixing tubes 31, are fed with gas vapor through conduits 72' and 73' which correspond to the conduits 72 and 73. Valves operated by valve stem handles 74' are for regulating the amount of vapor delivered to the jet members 71', and air for mixing with this vapor is obtained through holes as 70' in the mixing tubes 31.

Said conduits 72, 73, 72' and 73' lead from a gas pressure tank 75 which may be partly filled with gasoline or other volatile combustible material 76. This tank may be filled through an opening closed by a cap 77. A pump of any conventional construction, manipulatable by a reciprocal operating member 78, may be associated with the tank 75 as a means of creating pressure therein. Said tank 75 is supported at its rearmost end upon a pair of L-shaped brackets 79 which are respectively secured to the frame pieces 15 and 16. The front end of this tank is carried by a bracket 80 that depends from the rear end of a second tank 81.

Said tank 81 is for holding liquid cementitious material 82 such as a rubber cement which is to be applied to the side walls of the crevice 10 prior to deposit of the strip 63 therein. Support means for the tank 81 is provided in the form of upright rods 83 which engage the bottom of the tank and are carried at their lower ends in the machine frame. Access is had into the tank through an opening closable by a cap 84. Contained within the bottom of the tank 81 is a discharge spout 85 placed directly above the applicator brush 25. Said spout 85 is closable and regulatable in the amount of flow permitted by a needle valve member 86 under control of a handle member 87 which is rotatable to advance or retract a valve stem 88 in threaded relation with a flanged bushing 89. When the handle 87 is turned to withdraw the valve member 86 from its seat in the lower part of the spout 85,

the contents thus permitted to flow through the spout are guided onto the applicator member 25 by the tip portion 90 of the valve stem.

Operation of the machine

In setting the machine in operation, some of the cementitious material 82 will be disposed by means of the brush or applicator member 25 in the initial part of the crevice 10 which is to be filled with the strip 63. The control handles as 74 of all of the burners will have been opened to admit gas and the burners ignited for heating up the walls of the strip passage 64 and of the drum 34. The free end of the strip 63 will then be fed downwardly into the passage 64 where the flames from the burners comprising the jet members 71 will be played upon the strip to melt at least the surface portion thereof to impart to the strip a tacky surface. The thus treated end portion of the strip will then be projected through the strip guiding section at the lower end of the passage into said initial portion of the crevice and the machine advanced to run the drum 34 onto the strip for pressing it downwardly and firmly into the crevice. It will be observed that the passage 64 together with the burners comprising the jet members 71 serves as a heating means or chamber. Heat is imparted to the flight of the strip within the passage by the chamber walls including the periphery of the drum 34 which is also heated by burners. Such heat adds to the flexibility of the strip and to its softness, thus expediting the function of the pressing-in drum or roller 34 for depositing the strip in the crevice. Especially are the sides of the strip heated to a semi-liquid state by the flames which are played directly thereon from the burners upon the passage side walls 65 and 66. When the sides of the strip are thus treated they readily conform to minute irregularity in the sides of the crevice 10 when and after being pressed therewith by the roller 34.

The heat developed by the burners will be selectively regulated so the heat will be present in the right amount for melting the strip to the desired degree while it is traversing the passage at the chosen rate for depositing in the crevice.

Sealing of the strip to the crevice side walls is augmented by the cementitious material which is applied to these walls by the applicator brush 25, and the valve member 86 will also be adjusted to selectively regulate the amount of cementitious material which is discharged for applying to the crevice walls in accordance with the speed at which the machine is advanced.

The above described machine is also adaptable to the laying of a compressible strip into a crevice as 10; that is, a sealing strip which is simply compressed before being deposited in the crevice and then permitted to expand for gripping the crevice side walls and thus holding it in sealing relation therewith. Such a strip will ordinarily not be heated. It may be a tubular structure made of rubber such as that illustrated in cross section at 95 in Figs. 3 and 4; or it may be solid rubber, comminuted cork held together with a suitable binder, or any compressible material formed into a strip having the essential physical characteristics when in place.

This compressible strip will be wound upon a reel as 62 Fig. 1, and threaded downwardly through the passage 64 which will then have a pair of rollers 96, Fig. 3, secured for rotation in opposite sides of the strip guiding section. The position of these rollers relative to said guiding

section and to the roller drum 34 is illustrated by dotted lines in Fig. 1. Said rollers 96 will be spaced apart a distance not exceeding the width of the crevice 10 so the strip will be sufficiently compressed to enable it to be readily pressed into the crevice by the drum 34. The hollow strip 95 is compressed by the rollers as indicated in Fig. 3, and when it is laid within the crevice 10 it expands to some such shape as that illustrated in Fig. 4, the strip having longitudinal ribs 97 which impinging engage the crevice side walls. The strip may be, of course, of any other cross sectional shape. When the strip is made of rubber the burners will not be active during the laying process. Neither will these burners be active in any event when the strip being laid is not of a character for having a surface section thereof melt or soften under heat to form a plastic adhesive coating. It would be possible, however, to coat a compressible strip, as one of cork, with an asphaltic material and run the burners at low heat for melting the surface coating and thus cause the strip to be adhesively as well as impinging engaged with the crevice side walls when in place. During the laying of a compressible strip, the cleaner brush 24 will serve as before for cleaning the crevice, and the brush 25 may be used for coating the surface of the crevice with material from the tank 81.

Also in the above machine, the heating chamber 64 may be adapted for holding a bath of liquid sealing material, heated or unheated, and through which any kind of strip is passed to incur a coating of sealing material prior to being deposited in the crevice.

It may be found advantageous by some to reduce the mass of the unitary machinery for cleaning, coating and filling a crevice. For example, some may prefer to have the machine shown in Figs. 1 and 2 built into separate units as those shown respectively in Figs. 5 and 6. The machine in Fig. 5 is for cleaning and coating the crevice, whereas the machine shown in Fig. 6 is for laying the sealing strip.

Excepting for the arrangement of the running gear shown in Fig. 5 this machine is similar to the forepart of the machine shown in Figs. 1 and 2. Consequently, for expedience of disclosure, the parts shown in Fig. 5 which correspond to those shown in Figs. 1 and 2 are identified by the same respective reference characters with the letter *a* added. Said machine has a pair of guide rollers 100 and 26a with central flanges 102 and 32a which project downwardly into the crevice 10a for holding the course of the machine similarly to the flanges 32 and 33 shown in Fig. 1. Of these rollers the roller 26a is also a driving roller for driving the brushes 24a and 25a through the driven gears, sprockets and chains in the manner hereinabove described. In this manner the cleaning brush 24a is caused to rotate clockwise for sweeping the debris forwardly from the crevice. The applicator brush 25a is adapted to receive a liquid cementitious material from the tank 81a through the metering valve 85a for coating the crevice side walls. This machine is pushed and manipulated manually through a handle member 48a which is anchored in a socket 50a with bifurcated leg portions 103 (one being shown) upon opposite sides of the roller 26a and apertured for receiving the axle bolt 22a and frame bolts 104.

The strip laying machine shown in Fig. 6 is comprised of parts, which, for the most part, correspond respectively to the parts making up the

back portion of the machine shown in Figs. 1 and 2. These corresponding parts are identified by the same reference characters with the letter *b* added. Because of the diminished length of this machine the frame side member 15*b* is considerably shortened, and a flanged guide wheel 110, having a central flange 111 is added thereto for cooperating with the flanged guide wheel 27*b* for holding the course of the machine. This machine operates in all respects similar to the machine above described with reference to Figs. 1 and 2 so far as concerns the laying of a sealing strip.

An embodiment of the invention shown in Figs. 7 and 8 is designed for cleaning and filling irregularly formed cracks and crevices which frequently occur in concrete paving slabs or the like after they have been subjected to alternate expansions and contractions caused by changing weather conditions. This machine also embodies parts which correspond to and serve the same functions as parts already described with reference to Figs. 1 and 2. These corresponding parts will be identified by the same respective reference characters with the letter *c* added.

It will be observed that this machine omits the flanged guide rollers. In lieu of guide rollers the machine has a narrow extended section 120 upon the lower end of the passage member 64*c* for projecting into a crevice as 10*c*. Having but a single projection into a crevice as 10*c* enables the machine to be pivoted sharply about this point and thus to follow the tortuous course frequently defined by these fortuitous crevices.

The frame side members 15*c* and 16*c* are spaced apart at their front sections the same distance as at their back sections which are at opposite sides of the heating drum 34*c*, such spacing at the front being such as to accommodate a comparatively wide cleaning brush 121. Said brush 121 is of considerable axial length in the present machine to enable it to reach portions of a traversed crevice which may turn rather abruptly. The weight of the machine will be sufficient in respect of the flexibility of the bristles in the brush 121 as to bend the bristles upon opposite sides of the crevice sufficiently to enable those bristles in registry with a crevice to reach downwardly thereinto as illustrated at A in Fig. 7.

In this machine embodiment a hub portion of the heater drum 34 extending through the frame members 16*c* carries a gear 122 which meshes with a gear 123. Said gear 123 is disposed rotatively upon a shaft anchored in the frame side member 16*c* and in a side bracket 41*c*. Also rotatable upon this shaft is a sprocket wheel 124 which rotates with the gear 123. Driving force is transmitted from the roller drum 34*c* through the gears 122 and 123, the sprocket wheel 124, a chain 125 and a sprocket wheel 126 which is connected with the hub of the brush 121 for driving the same.

The machine as shown in Figs. 9 and 10 is for unwinding and laying a sheet of roofing paper or the like upon a flat surface and for adhesively attaching the sheet to the surface by means of a semi-liquid sealing material obtained by applying heat to and melting a strip of the sealing material as it is unwound from a reel. This machine is built about a frame which comprises a pair of identical L-shaped side pieces 130 each of which has a horizontal leg 131 and an upright leg 132, said legs being joined by a diagonally positioned gusset member 133. The horizontal frame legs 131 are held in selected spaced rela-

tion by a spanning plate 133' which has at its ends downwardly directed flanges 134 which are respectively secured to the members 131 by bolts as 135. Crossbars as 136 and 137 are similarly secured between the upright legs 132 to which they are held by means of bolts as 138. A pair of front wheels 145 are journalled upon a front axle 146.

An axially removable reel-holding rod 139 is carried in the upper ends of the vertical frame members or standards 132 for rotatively supporting a roll 140 of roofing paper or the like. An additional rod 141 is removably supported between the upright members 132 for rotatively supporting a pair of reels 142 and 143 comprising flexible strips 144 of meltable sealing material such as asphalt meltable at low temperature.

A flight 147 unwound from the roll 140 extends downwardly in engagement with the periphery of the strip material upon the reels 142 and 143 and about the forward and under periphery of a roller 147' so that when the machine is advanced, the pressure upon the sheet by this roller, together with the adhesive connection of the laid portion of the sheet with the surface to which it is being applied, will provide an anchorage for pulling upon the flight 147 and causing the sheet to be unwound from the roll 140. The machine is pushed forwardly by manual force applied to a handled bar 148 secured crosswise to the upper end of a steering shaft 149 which is anchored in a socket 150. This socket 150 is secured to a cross-rod 151 extending between and anchored in the frame uprights 132.

A pair of arms 152 (of which one is shown) are pivotally secured upon a rod 153 which also is anchored in the uprights 132. These arms 152 rotatively carry a roller 154 upon a spindle 155. Said arms 152 are urged counterclockwise by a spring 156 so as to constantly press the roller 154 against that portion of the flight 147 which engages the wound strip material upon the reels 142 and 143. This frictional engagement of the flight 147 with the wound strip material causes the strip material to be unwound from the reels 142 and 143 at a speed corresponding to that at which the paper is wound from its reel, irrespective of the depleted condition of the roll 140 and of the reels 142 and 143.

A pair of spaced-apart guide rollers 157 and 158, Fig. 10, is provided for each of the strips 144. Said rolls are carried rotatively between the opposed parts of brackets 159 and 160 which are anchored respectively to a frame diagonal member 133 and to a frame upright 132. An additional guide roller, 161, is also disposed between the opposed sections of each set of brackets 159 and 160.

Immediately below and forwardly of each guide roller 161 there is a pair of friction rollers 162 and 163 which have grooved peripheries for complementally receiving and gripping the associated strip 144 and pulling it from the adjacent roller 161. The roller 162 of these paired rollers, Fig. 9, is journalled upon a short shaft 164 reciprocally carried in an elongated opening 165 in a bracket 166 secured to the adjacent frame member 133. The other roller, 163, of these pairs is rotatively mounted upon a stub shaft 167 that is anchored within a bracket 168 secured to the associated frame member 131. Also rotatively mounted upon each shaft 167, and connected with its associated gear 163 for mutual rotation, is a sprocket wheel 169 driven by a chain 170 from a sprocket wheel 171 which is

fixed for rotation with the roller 147'. Each of the reciprocal shafts 164 is connected by a tension spring 172 with the adjacent shaft 167 for yieldingly urging its associated roller 162 toward its mated roller 163 so that the unwinded flight of the strip 144 will be yieldably and firmly engaged by these rollers.

Heating means comprising a retort or chamber 173 and a burner generally designated 174 are respectively provided for the strips 144. With particular reference to the heating means for the right-most strip 144, Fig. 10, an opening 175 is present in the top of the chamber for receiving the strip as it passes from the rollers 162 and 163. A flame from the burner is directed against the strip 144 shortly after it enters the heating chamber. The melting point of the strip is such that it melts quickly from the heat absorbed from the chamber walls which become heated from the flame and by the heat absorbed directly from the flame played upon it. The heated melted liquid material falls into an elongated distributor tube 176. The tubes 176 extend laterally of the machine and slightly downwardly toward one another. The melted material in the bottom thereof is constantly heated and thus kept semi-liquid by the hot blast from the burner, which blast is discharged through the ends of said distributors. Each distributor has an axially extending slit-like discharge opening 177 within its lower side through which the sealing material egresses and is spread uniformly over a space coextensive with the length of the distributor. While the slit-like openings in the bottoms of these distributors are illustrated as a single opening there may be a series of openings spaced longitudinally of these members, and such a connotation is to be given to the term "opening" as used in connection with these parts in the appended claims.

The burners 174 are of any conventional construction. A combustible gas is supplied thereto through conduits 178 and 179 from a pressure tank 180. Control handles 182 are rotatable for controlling the degree of opening of valves within the burners to determine the amount of fuel passed into the burner mixing tubes 183 and hence the intensity of the flame directed into the heating chambers 173.

While I have shown two reels of meltable sealing strip material upon the machine, obviously a machine of this kind is adaptable for using a single reel with a corresponding single set of guide rollers as 151, 158 and 161, a single heating unit and a single distributor. Also it is within the scope of the present invention to provide any additional number of sets of guiding rollers, heating units and distributors for handling strips as they are unwound from the like number of reels.

In the operation of this machine, after an unwound end portion of the paper roll 140 has been threaded downwardly between the roller 154 and the periphery of the wound sealing strips and beneath the roller 147', and after the sealing strips have been threaded about and between their respective rollers and inserted into their respective heating chambers 173 and the burners lighted for melting the portion of the strips within these chambers, the machine may be advanced by an operator while grasping the handle bar 148. The melted material will then be discharged through the bottoms of the distributors 176 to cover an area with the melted sealing material prior to the paper being laid

upon that area and pressed into position by the roller 147'.

It will be observed, since the strip material is fed into the melting chambers 173 at the same speed at which the paper is unwound for laying upon the surface, that the amount of sealing material deposited beneath the paper can be accurately determined by using a strip of selected cross-sectional area. The amount of fuel consumed in the combustion chambers 173, such amount being regulated by the control handles 182, will be determined by the cross-sectional area of the strip fed into the chambers and also by the rate of speed at which the machine is to be advanced and hence the rate at which the strip is fed into such chambers. Obviously, the greater the surface area presented by the strips in the combustion chamber, the more quickly can the strips be melted, wherefore it follows that a greater volume of strip material can be melted per unit of time when a plurality of strips are fed into one or more chambers.

A further advantage of employing a plurality of burners and combustion chambers for melting the material is that the distributors can be shortened so that the sealing liquid may flow a shorter distance before being discharged.

I claim:

1. A crevice filling vehicular machine comprising a frame, means on said frame for holding a length of thermoplastic crevice filler strip in a manner that it is payable out endwise therefrom so a portion of a flight payed out from said holding means is insertable in a section of a crevice to be filled by the strip to provide an anchorage for the strip whereby it is caused to pay out as the machine is advanced along the crevice, guide means on said frame, said guide means being disposed for embracing an unwound section 30 of said strip flight adjacently to the portion inserted in the crevice and in registry with and in close proximity with the crevice for directing the payed out strip into the crevice during such advancement of the machine, means for heating 35 said strip flight to increase its plasticity and thus facilitate the disposal of the strip into said crevice, and means for disposition in registry with the crevice in trailing relation with respect to said guide means and for pressing the heated 40 strip into the crevice pursuant to advance of the machine.

2. In a vehicular machine for depositing a wound but unwindable sealing strip which is meltable when subjected to heat, the combination 45 of holding means for such a wound strip and adapted for the unwinding of such strip pursuant to advancement of the machine while the free end of the strip is held fast, a heated passage for receiving the strip as it unwinds, and means for predeterminedly directing the heated 50 portion of the strip.

3. In a mobile machine for filling paving crevices or the like with a preformed strip which becomes tacky when heated, strip holding means 55 adapted to axially feed said strip, heating means for receiving the strip as it is fed from said holding means, and strip guiding means arranged for receiving the strip as it emerges from said heating means and disposable in registry with 60 and in close proximity with a crevice to be filled.

4. In a machine for meting out and depositing within a traversed path a strip of sealing material which becomes tacky when subjected to 70 heat, the combination of strip holding means

from which the strip can be withdrawn endwise, guiding means for directing the meted out portion of the strip predeterminedly into said path, and heater means for shrouding a section of the strip between said strip holding means and said guiding means, and the heat intensity of said heater means being regulatable in intensity to melt only the outer portion of said strip as it passes therethrough for guiding to the place of deposit.

5. In a machine for meting out and depositing within a traversed path a strip of sealing material which becomes tacky when subjected to heat, the combination of strip holding means from which the strip can be withdrawn endwise, guiding means for directing the meted out portion of the strip predeterminedly into said path, a heater passage for shrouding a section of the strip between said strip holding means and said guiding means, and torch means adapted to direct a flame substantially upon the shrouded section of a strip.

6. In a mobile machine for filling paving crevices or the like with a preformed strip which becomes tacky when heated, the combination of means adapted to axially feed said strip, guiding means for directing the strip into the crevice as it is fed from said holding means, heater means adapted to enclose a section of the strip between said feeding means and said guiding means, a heating roller to the rear of said guiding means and adapted to press the strip into the crevice as the machine advances, and said heating roller forming a side wall of said heating means.

7. In a machine for filling a paving crevice or the like with a preformed strip, the combination of means for axially feeding said strip, a guide roller adapted to bear weight of the machine and projectable into the crevice to cause the machine to follow said crevice, a cleaner brush rotatable about an axis disposed transversely of the machine and of a width to enable the bristles thereof to project downwardly into the crevice, a crevice liner applicator member rearwardly of said brush and also rotatable about an axis disposed transversely of the machine and of a width and diameter to provide for its projecting downwardly into the crevice, a reservoir above said applicator member, means for directing contents of the reservoir upon said applicator member, means actuated by said guide roller for rotating said applicator member and for rotating said brush in the opposite direction of said roller during machine advancement, and means rearwardly of said applicator member for receiving and directing the axially fed strip into the crevice.

8. In a machine for filling a paving crevice or the like with a preformed strip, the combination of means for axially feeding said strip, a roller adapted to bear weight of the machine, means projecting into the crevice to cause the machine to follow the crevice, a cleaner brush rotatable about an axis disposed transversely of the machine and of a width to enable the bristles thereof to project downwardly into the crevice, a crevice liner applicator member rearwardly of said brush and also rotatable about an axis disposed transversely of the machine and of a width and diameter to provide for its projecting downwardly into the crevice, a reservoir above said applicator member, means for directing contents of the reservoir upon said applicator mem-

ber, means actuated by said roller for rotating said applicator member and for rotating said brush in the opposite direction of said roller during machine advancement, and means rearwardly of said applicator member for receiving and directing the axially fed strip into the crevice.

9. In a machine for filling paving crevices or the like with a preformed strip that tends to liquify when heated, running gear for said machine, a brush member rotatable about an axis disposed transversely of the machine, operating means for said brush and actuated by said running gear for rotating said brush in the opposite direction to the rotation of said running gear, means adapted to axially feed said strip, means for guiding the axially fed strip into the crevice, and heater means embracing a portion of the strip between said strip feeding means and said guiding means and adapted to heat at least a surface portion of said strip for transforming such portion of the strip into a semi-liquid condition.

10. In a machine for filling paving crevices or the like with a preformed strip, a running gear including a plurality of rollers of which at least a portion are adapted to project downwardly into a crevice to serve as guide means for the machine, an applicator member rotatable about an axis transversely of said machine and adapted to project downwardly into said crevice, means for rotating said applicator, a reservoir on said machine including means for directing contents thereof onto said applicator member, means adapted to axially feed said strip, means rearwardly of said applicator member for receiving and directing the fed portion of the strip into said crevice, and heating means adapted to enclose a portion of the strip disposed between said holding means and said guiding means and operable to heat at least the surface portion of the strip to transform such portion into a semi-fluid state preparatory to being directed into the crevice by said guiding means.

11. The method of filling a crevice with a filler strip having a surface portion convertible into a semi-liquid when sufficiently heated, comprising the steps of conveying a wound unit of such strip along the crevice, unwinding the strip from the unit during such conveyance, heating the strip as it unwinds from the unit to so convert said surface portion thereof, and depositing the heated strip in the crevice.

12. A crevice filling vehicular machine comprising a frame, means on said frame for holding a length of thermoplastic crevice filler strip in a manner that it is payable out endwise therefrom so a portion of a flight payed out from said holding means is insertable in a section of a crevice to be filled by the strip to provide an anchorage for the strip whereby it is caused to pay out as the machine is advanced along the crevice, means for heating said strip flight to increase its plasticity and thus facilitate the disposal thereof into said crevice, and means connected with said frame in position to bear upon the portion of the strip flight substantially as it is inserted into the crevice and for pressing upon the inserted portion of said strip flight for forcing the same into the crevice.
